DISHWASHER

John E. Long, Multnomah, Oreg.

Application January 28, 1929. Serial No. 335,488

5 Claims. (Cl. 141—9)

The principal object of my invention is to provide dish washing apparatus which is conveniently operated, simply constructed and inexpensively manufactured, and which is specifically devised to be used in conjunction with an open-top receptacle for holding the dishes to be washed, the dish washing apparatus being carried wholly by a member constituting a cover for such receptacle.

10 A further and more specific object of my invention is to provide a perforated basket-like receiver adapted to be arranged within the receptacle, such receiver being provided with devices for arranging and holding the dishes in position in which they can be washed effectively. Such basket-like receiver is separate from the receptacle and thus when such dishes have been washed they may be lifted directly out of such receptacle without being removed from such receiver and will be held in position so that the excess water adhering to them will drain off.

15 A further object of my invention is to provide washing apparatus of this character with power mechanism capable of producing agitation of the washing liquid in the receptacle, and power for external power takeoff devices adapted to drive auxiliary scouring or polishing units. Such devices are arranged to divert a minimum amount of power from the washing apparatus so that such auxiliary units can be driven simultaneously with the washing apparatus or independently thereof, such power takeoff devices further being devised to permit variable rates of operating speed for such auxiliary units.

20 A further object of my invention is to provide means in conjunction with such washing apparatus by which a supply of soapy material is arranged to be acted upon by a supply of water to provide soapy liquid for washing such dishes.

25 Further features of my invention and the details of construction and the mode of operation are hereinafter described with reference to the accompanying drawings, in which:

30 Fig. 1 is a cross section thru such washing apparatus;

35 Fig. 2 is a horizontal sectional view showing the details of the power takeoff devices for driving auxiliary units;

40 Fig. 3 is a vertical sectional view showing said power take-off device;

45 Fig. 4 is a perspective view of the agitator of such washing apparatus with a portion of the wall broken away to show details of construction thereof;

Fig. 5 is a bottom view of such agitator taken in the direction of the arrow 5 in Fig. 4;

Fig. 6 is a sectional view taken substantially on the line 6—6 in Fig. 1 showing the basket-like receiver for holding the dishes. 60

My improved washing apparatus is adapted to be housed within an open top receptacle *a* which is preferably provided with a valve-operated drain *d* located at its lowest point. Within such receptacle a basket-like dish receiver *c* is adapted 65 to be arranged, such receiver extending substantially the entire height of the receptacle *a*. In such receiver guides *b* are arranged for holding the dishes in place so that an agitator *e*, in one type of my invention, may throw water onto such dishes in the most efficient manner. Such agitator *e* is driven by a motor *f*, preferably electrical, such agitator being removably connected to such motor by a coupling *g*. 70

The receiver *c* is formed so as to provide a 75 central space *c'* within which such agitator operates and such centrally formed portion *c2* extends substantially the entire length of the agitator to prevent dishes from striking such agitator and thus interfering with its operation. When a rotary type of agitator is used, devices, such as spaced guide members *c3*, are arranged in such receiver to hold the dishes in vertical planes spaced apart and preferably extending tangential to the path described by the vanes of the agitator. 80 In any event, such dishes or the major portion thereof, are arranged substantially radial from said centrally formed portion *c2* towards the rim of such basket-like container. Such guide rods *c3* are spaced a substantial distance from the floor *c4* of such receiver to hold such dishes securely. 85

I further provide a pocket *c5* defined by two of the radiating rods *c3* and the connecting element *c6*, in which silverware and the like can be arranged on end. Inasmuch as dishes and other utensils commonly used vary substantially in size and dimensions, I provide a portion of such receiver with devices for positioning such occasional dishes as bowls and platters. As is shown in Figs. 1 and 6, this portion of the receiver is arranged with a series of sinuously curved members *c7* forming vertical pockets or recesses for engaging the edges of such dishes. Such pockets or recesses are arranged quite closely together and such members extend substantially at an opposite tangent to the members *c3*, as is shown in Fig. 6, so that such dishes carried in such pockets or recesses will extend at the same tangent as the dishes held by the members *c3*, this 90 100 105 110

being shown in dotted outline in Fig. 6. The members *c7* defining such pockets or recesses are preferably made of flexible but resilient wire so that such members *c7* can be distorted slightly 5 to permit such dishes to be placed angularly in the recesses formed therein.

The agitator *e* is preferably conical in section, as shown in Fig. 4, and is formed with a hollow shell *e8* carrying outstanding vanes *e2* and *e3*.

- 10 The vanes *e2* are substantially flat and extend radially from the axis of rotation of such agitator so as to throw water with which they engage outwardly in planes normal to such axis. The vanes *e3* are curved or cupped slightly so 15 that portions thereof extend angularly to such axis of rotation and thus water engaged by such vanes *e3* will be thrown, in part, out of such normal planes and upwardly therefrom.

The water is thus discharged from such vanes 20 by displacement and centrifugal forces and tends to create a region of decreased pressure within the hollow shell of such agitator. Adjacent the base of such vanes a series of perforations *e4* are arranged, thus causing circulation of the water contained in the receptacle *a*, the water being drawn thru the open mouth *e5* of the agitator and forced outwardly thru the perforations *e4* by the rotation of such agitator. To increase 25 such circulation, I provide a series of propelling vanes *e6* about such open mouth *e5* and such vanes are inclined and proportioned relatively to the portions of such agitator to throw or force liquid into the hollow body of such agitator.

Preferably at the upper portion of such agitator I provide a soap chamber separated from the remainder *e7* by a screen-like or perforated partition *e11*. In such chamber a supply of soapy material, diagrammatically shown in Fig. 4, can be held and the ascending stream of water within 30 such agitator will be forced upwardly from the chamber *e7* to produce soapy solutions and suds which will be forced outwardly thru the perforations *e9*, which are screen-covered to prevent the inefficient discharge of such material from the soap chamber. I provide a filling opening into 35 the soap chamber, which opening is normally closed by a plug *e10*, as shown in Fig. 4.

The motor *f* and the agitator *e* are mounted upon and carried by cover *h*, which seats upon 40 the open top of the receptacle *a*, as shown in Fig. 1. Such cover preferably is substantially imperforate so that the washing liquid within the receptacle *a* will not be discharged therefrom. A filling connection *i* is arranged thru such cover *h*, primarily arranged to provide washing liquid 45 for the receptacle *a* so that the liquid within such receptacle can be drained thru *d* and fresh liquid be replaced thru the connection *i*. For example, if it is desired to rinse the dishes with 50 fresh clean water, this may be done in this manner. The opening *i* serves a further purpose, however. The relatively great speed of the agitator *e* builds up increased pressure within the receptacle *a* and under the cover *h*, which tends 55 to discharge foamy suds thru the connection between the cover and the receptacle. The filling opening *i* permits such increased pressures to be dissipated and thus packing or close-fitting joints about the mouth of the receptacle are not 60 required. The joint between the two halves of the casing preferably is made, as is shown in the drawings, with an overlapping connection and the marginal edges of the two halves terminating in complementary, oblique angular portions 65 adapted for mutual engagement. This provides

a close fitting joint, which is not disturbed by pressure from within the casing, for the reason set out above. The provision of upwardly facing or cupped blades, and the fact that the motor is carried by the upper half of the casing, tends further to hold the cover firmly in place and said overlapping joints in engagement.

Power is supplied to the member *f*, if it is an electrical motor, thru an electrical plug connection *j*. Preferably there are a series of connections to such motor having varying resistances so as to give such motor corresponding varying speeds. This being common in the art, it is therefore not shown.

The shaft of such motor *f* extends upwardly thru such motor, and a gear case *k* is arranged on the top of such motor housing. A central shaft *k'* in such housing engages such motor shaft by a clutch-like end, as shown in Fig. 2 in the drawings. Drive pinion *k2* is mounted upon such shaft and is normally out of mesh with the remaining gears housed within such casing. Spaced about such drive pinion *k2* are gears *k3*, *k4* and *k5* varying in diameter to provide various speeds of operation for the shafts 100 upon which they are mounted. Such gears *k3*, *k4* and *k5* are mounted upon coil springs *k6* surrounding their drive shafts respectively, such springs tending to move such gears laterally out of mesh with the drive pinion *k2* and hold them 105 in the position shown in Fig. 3. The upper ends of the shafts *k7*, *k8* and *k9* are provided with clutch ends, as shown in Fig. 2, adapted to engage with the flexible shaft *l* for the auxiliary devices 110 driven thereby. Such shaft is incased within a fitting *m* adapted to be engaged with lugs *n* upon the upper surface of the gear case *k*. Such fitting *m* and the lugs *n* are proportioned and arranged relatively so that when they are in engagement the shaft *l* is forced downwardly 115 against the shafts *k7*, *k8* and *k9*, with which such flexible shaft *l* is adapted operatively to engage, with sufficient force to compress the spring *k6* surrounding that particular shaft and move the 120 gear carried thereby into engagement with the pinion *k2* so that a complete operative connection is made between the shaft of the motor *f* and the flexible shaft *l* for the auxiliary devices. 125

I claim:

1. In a dishwashing machine, a casing comprising two complementary stacked halves, the entire side walls of said casing flaring outwardly from the top and bottom portions thereof to the points at which the halves meet, the lower half of 130 said casing adapted to contain a dish rack and a body of liquid, a rotatable washing device depending into the lower casing half and said dish rack, said washing device comprising an agitator head adapted to circulate said body of liquid thru 135 said rack and along the casing sides, the flare of the casing directing said washing liquid vertically thereof and about said rack and means to rotate said washing device.

2. In a dishwashing machine, a casing comprising two complementary stacked halves, the entire side walls of said casing flaring outwardly from the top and bottom portions thereof to the points at which said halves meet, a portion of the upper half of said casing depending centrally 145 into the interior thereof, a motor housed in said depending portion, the lower half of said casing adapted to contain a dish rack and a body of liquid, a rotatable washing device having driving connection with said motor and depending 150 into the lower casing half and said dish rack,

- said washing device comprising an agitator head adapted to circulate said body of liquid thru said rack and along the casing sides, and the flare of the casing directing said washing liquid vertically thereof and about said rack. 5
3. In a dishwashing machine, a casing comprising two complementary stacked halves, the entire side walls of said casing flaring outwardly from the top and bottom portions thereof to the points 10 at which said halves meet, a motor carried by the upper casing half, the lower half of said casing containing a dish rack and adapted to contain a body of liquid, a rotatable washing device depending from said motor into the lower casing 15 half and said dish rack, said washing device comprising an agitator head adapted to circulate said body of liquid thru said rack and along the casing sides, the flare of the casing directing said washing liquid vertically thereof and about said rack, 20 said dish rack provided with a vertical perforated well extending about said washing device and upwardly to a plane adjacent the top of said washing device, said agitator head provided with a cupped active surface facing upwardly, and 25 adapted in operative position to be immersed in said washing liquid.
4. In a dishwashing machine, a casing comprising two complementary stacked halves, the entire side walls of said casing flaring outwardly from the top and bottom portions thereof to the points 30 at which said halves meet, a motor carried by the upper casing half, the lower half of said casing containing a dish rack and adapted to contain a bdy of liquid, a rotatable washing device depending from said motor into the lower casing 35 half and said dish rack, said washing device com-
- prising an agitator head adapted to circulate said body of water thru said rack and along the casing sides, the flare of the casing directing said washing liquid vertically thereof and about said rack, said dish rack provided with a vertical 80 perforated well extending about said washing device and upwardly to a plane adjacent the top of said washing device, said agitator head provided with radial blades of different degrees of vertical angularity, one blade having an active surface facing upwardly, and adapted in operative position to be immersed in said washing liquid. 85
5. In a dishwashing machine, a casing comprising two complementary stacked halves, the entire side walls of said casing flaring outwardly from the top and bottom portions thereof to the points at which said halves meet, a motor carried by the upper casing half, the lower half of said casing containing a dish rack and adapted to contain a body of liquid, a rotatable washing device depending from said motor into the lower casing half and said dish rack, said washing device comprising an agitator head adapted to circulate said body of water thru said rack and along the casing sides, the flare of the casing directing said washing liquid vertically thereof and about said rack, 90 said dish rack provided with a vertical perforated well extending about said washing device and upwardly to a plane adjacent the top of said washing device, said agitator head provided with radial blades of different degrees of vertical angularity, and adapted in operative position to be immersed in said washing liquid. 95
